UNITED STATES PATENT OFFICE

GEORGE A. JONES, OF LYNN, MASSACHUSETTS, ASSIGNOR TO SHOE PRODUCTS, INC.,
OF LYNN, MASSACHUSETTS, A CORPORATION OF MASSACHUSETTS

SHOE

Original application filed January 29, 1927, Serial No. 164,465. Divided and this application filed December 17, 1927. Serial No. 240,711.

The invention to be hereinafter described relates to shoes, and more particularly to a shoe which is specially manufactured so that heel and metatarsal arch supporting cushions may be easily applied thereto.

Heretofore various devices have been applied to shoes for supporting the metatarsal arch of the foot, but so far as I am aware, they have been expensive, difficult to apply, and unsatisfactory. One of the purposes of the present invention, therefore, is to provide a shoe which is of usual construction with the exception of a simple unobjectionable change therein which enables heel and metatarsal arch supporting cushions or either of them to be quickly and easily applied to the shoe.

The character of the invention may be best understood by reference to the following description of good forms thereof, shown in the accompanying drawings, and the process of manufacturing the same.

In the drawings:

Fig. 1 is a perspective view of an insole having cushion locating and holding holes therein, and shows the slugs removed in punching the holes;

Fig. 2 is a longitudinal section through a portion of a man's shoe embodying the invention;

Fig. 3 is a bottom view of the heel cushion;

Fig. 4 is a bottom view of the metatarsal arch supporting cushion;

Fig. 5 is a longitudinal section through a portion of the shoe and showing the heel and metatarsal arch supporting cushions applied to the insole after removal of the slugs from the holes therein;

Fig. 6 is a longitudinal section through a portion of a lady's turned shoe embodying the invention;

Figs. 7 and 8 are respectively perspective views of a shank and a fore part filler; and

Fig. 9 is a vertical section through a portion of the shoe shown in Fig. 6 and showing the heel and metatarsal arch supporting cushions applied to the shank and fore part filler respectively after removal of the slugs from the holes therein.

50 Referring to the drawings, 1 (Fig. 1) designates an insole having a hole 3 punched in the heel portion of the insole and a hole 5 punched in the ball portion of the insole, said holes being of general oval form and produced by punching out slugs 7 and 9 from the insole. These slugs are restored to or left in the holes in the insole, and may be held removably therein by webs 11 and 13 of cloth or paper and having areas larger than the slugs and secured to the upper and lower surfaces of the insole by a suitable adhesive. 55

The insole described above may be built into a shoe in the process of manufacturing the same. In this process the upper 15, counter 17 and insole may be lasted in the usual manner, and then the outsole may be applied. The hole in the heel portion of the insole is so located and of a size such that in punching the same it is directly above the cavity formed by the inturned margins 19 of 60 the upper, counter and lining which are between the insole and the outsole. The hole in the ball portion of the insole is of an area and location such that it is in away from the inseam of the shoe. Thus the making of 65 these holes in the insole does not have any destructive effect upon or weaken the shoe. 70

75 The heel cushion may be substantially the same as that disclosed in my copending applications Serial Nos. 156,927 and 156,928, 80 both filed December 24, 1926. It is made of high grade rubber and comprises a diaphragm 21 (Fig. 3) having a collar 23 projecting down from the bottom thereof and of oval shape and appropriate size to fit into the hole 3 in the insole. The diaphragm is substantially larger than the hole and has a marginal portion which rests upon the upper surface of the insole surrounding the hole. 85

90 The construction of this diaphragm is such that when its collar is in the hole in the insole and the wearer of the shoe is walking, the diaphragm may flex up and down with pulsatile action, and will conform to the shape of the base of the heel of the wearer of the shoe. 95 The oval shape of the hole and the collar of the cushion will prevent the diaphragm from turning out of its normal proper position. Also the collar in the hole will prevent any 100

shifting of the diaphragm longitudinally or transversely of the insole.

The metatarsal arch supporting cushion may be substantially the same as disclosed in said application Serial No. 156,927. It is made of high grade rubber and comprises a diaphragm 25 (Fig. 4) having a collar 27 projecting down from the bottom thereof, said collar being of oval form and of proper size to fit into the hole 5 in the ball portion 10 of the insole. Projecting up from the diaphragm is a protuberance 29 (Fig. 5) which is suitably formed to furnish the proper support for the metatarsal arch of the foot. The diaphragm has a margin of substantial area 15 which rests upon the upper surface of the insole. When the wearer is walking, the diaphragm and its protuberance are adapted to flex up and down with pulsatile action which 20 will operate desirably to exercise and strengthen muscles of the foot and restore them to normal healthy condition, so that they will properly support the metatarsal arch of the foot.

25 The oval shape of the collar 23 of the arch supporting cushion and the oval shape of the hole 5 in the insole will prevent dislocation 30 of the cushion from its proper position. It cannot shift longitudinally or transversely of the insole, and it cannot turn.

By my invention a shoe is provided of usual construction with the exception that the slugs are punched from the insole and left 35 and secured therein so that to outward appearances the shoe is not different from the ordinary shoe. Shoes thus manufactured and supplied to retailers will be in readiness to receive the heel and metatarsal arch supporting cushions if a customer so desires. 40 In applying these cushions it is merely necessary to remove the slugs from the holes in the insole, present the heel and metatarsal arch supporting cushions to the insole and insert their collars into the holes. These are 45 simple operations quickly and easily accomplished. The hole is so located in the ball portion of the insole that if a person is fitted with a shoe of correct size, the metatarsal arch supporting cushion will be properly located to furnish the desired support for the 50 arch.

A shoe provided with these cushions can be worn as an ordinary shoe, since they do not project into and occupy the space originally designed to receive the foot.

55 Goodyear welt, McKay, turned shoes and other types of shoes may be prepared to embody the present invention, in order that they may be adapted to receive the cushions described.

60 Referring now more particularly to Figs. 6 to 9, a lady's turned shoe is shown therein and comprises the upper 31, sole 33, heel 35, shank 37 and fore part filler 39. The shank 65 and the fore part filler have mating feathered

ends 41 and 43 which may be secured together by a staple. The hole 45 is made in the shank to receive the heel cushion, and the hole 47 is made in the fore part filler to receive the metatarsal arch supporting cushion. The shank and the fore part filler preferably have the holes punched therein before they are built into the shoe. The slugs 49 and 51 which are punched out in producing the shank hole and fore part filler hole, are left 70 in their holes and are removably held therein by webs 53 and 55 of cloth or paper and having areas larger than the slugs and secured to the upper and lower surfaces of the shank 75 and filler by suitable adhesive.

80 The cushions for application to the shank and the fore part filler may be similar to those described for the man's shoe, with the exception that the heel cushion necessarily would be made smaller and preferably its 85 collar is of the same size as the collar of the metatarsal arch cushion. The holes 45 and 47 for receiving the collars preferably are made of the same size.

If the lady's shoe is constructed with a full 90 length filler, it would be similar to the insole shown in Fig. 1, but shaped appropriately for a lady's shoe.

This application is a division from my application Serial No. 164,465, filed January 29, 1927, claiming the process disclosed herein, said application having resulted in Letters Patent No. 1,675,711, dated July 3, 1928.

The term "insole" employed in the claims is also to be regarded as generic to a full 100 length filler and to a shank and fore part filler.

105 It will be understood that the invention is not limited to the embodiment shown and that various deviations may be made therefrom without departing from the spirit and scope of the appended claim.

I claim:

110 As an article of manufacture, a shoe comprising an upper, counter, insole, outsole and heel, said insole having cushion locating and holding holes punched therethrough at the heel and ball portions of the insole, the hole at the heel portion being within the inturned margins of the upper and counter, and the 115 hole at the ball portion being in front of the inseam, and readily removable slugs in said holes, above the outsole and having upper surfaces flush with the upper surface of the insole, said slugs being adapted to be removed 120 that heel and metatarsal arch supporting cushions may be applied to said holes.

GEORGE A. JONES.
